UNITED STATES PATENT OFFICE.

CLAUDE D. STILWELL, OF HAMAR, NORTH DAKOTA.

WELL-AUGER.

1,241,051.

Specification of Letters Patent. Patented Sept. 25, 1917.

Application filed April 11, 1917. Serial No. 161,227.

To all whom it may concern:

Be it known that I, CLAUDE D. STILWELL, a citizen of the United States, residing at Hamar, in the county of Eddy, State of North Dakota, have invented certain new and useful Improvements in Well-Augers; and I do hereby declare the following to be a full, clear, and exact description of the invention, such as will enable others skilled 10 in the art to which it appertains to make and use the same.

This invention relates to new and useful improvements in well augers.

The primary object of the invention is to 15 provide a well auger with a cutting element which is adapted to close the bottom of a cylindrical receptacle to retain the material which has been cut thereby within the receptacle.

20 A further object of the invention is to provide a well auger in which the receptacle may be emptied of its contents when the device has been removed from the well.

25 A further object of the invention is to provide a well auger in which the cutting element is operated automatically to prevent discharge of material from the cylinder upon the withdrawal of the device from the well.

30 Referring to the drawings:

Figure 1 is a vertical sectional view showing the auger in its operative position.

Fig. 2 is a vertical sectional view showing the cutting member in its closed position.

Fig. 3 is a bottom view, and

Fig. 4 is a perspective view of the blank from which the cylindrical receptacle is formed.

40 Referring more specifically to the drawings the device comprises a cylindrical casing 1 formed of sheet metal, and extending across the upper end of the cylinder is a bar 2 which is preferably of cast metal and 45 is provided with a central squared opening 3, the purpose of which will be hereinafter set forth.

50 As shown in Fig. 3 a bar 4 extends across the lower end of the cylinder, said bar 4 being arranged in a plane at right angles to the first mentioned bar 2 thus aiding in bracing the cylinder.

55 Extending upwardly from the bar 4 is a standard 5, this standard 5 being arranged centrally of the cylindrical casing 1, and passing through the squared opening 3 of

the bar 2 is a squared rod 6, the lower extremity of which is provided with a recess 7 which extends longitudinally thereof and is adapted to receive the vertical standard 5. 60

Pivottally connected to the bar 6 as by means of the collar 8 is a link 9, said link extending downwardly through the bottom of the cylindrical member and is connected to a cutting element 10 by means of a nut 11 as shown in Fig. 3.

This cutting element 10 is hinged as at 12 to a stationary portion 14 of the bottom to permit of a vertical movement thereof to close the bottom of the cylindrical member during the operation of removing the device from the well thus preventing the discharge of any material within the cylindrical member.

Hinged to the transverse brace 4 is a semi-circular disk 14 which is secured thereto by means of the hinges 15, said disk 14 being maintained in its closed position by means of a suitable latch 16.

As shown in Fig. 4, the blank from which 80 the cylindrical member 1 is formed comprises a substantially rectangular sheet of metal, the lower edge of which is cut away as at 17, and it will be seen that when the edges of the ends of this blank are brought 85 together to form the cylindrical member a depending portion 18 is provided on the lower edge thereof, and it is within this depending portion that the cutting member 10 is adapted to move when not in opera- 90 tion.

From the foregoing it will be seen that when the device is inserted into an opening in the ground and rotary movement given to the squared shaft 6, the cylindrical member 1 will be rotated and will carry with it the cutting member 10 which owing to the vertical thrust on the squared shaft 6 and its link connection therewith will be projected as shown to perform the cutting 100 operation. When, however, the cylindrical member 1 has become filled to the desired amount with material severed by the cutting member 10, the same is withdrawn from the opening by pulling vertically on the squared shaft 6 and it will be seen that during this withdrawing action the link 9 operates to move the cutting member 10 within the bottom of the cylindrical member thus closing the bottom thereof and preventing discharge of the material contained therein. This operation is permitted by 110

reason of the sliding engagement between the recess 7 in the lower extremity of the squared shaft 6 with the vertically extending member 5 hereinbefore described. When 5 the device has been entirely removed from the opening, the latch member 16 may be operated to permit of the semi-circular bottom 14 swinging on its hinges to entirely discharge the contents of the cylindrical member.

10 Having thus described the invention, what is claimed is:—

15 1. A device of the character described, comprising a cylindrical casing, means for closing a portion of the bottom of said casing, means for rotating said cylindrical casing, and a cutting element connected to said casing rotating means and adapted to close the remainder of the bottom of the 20 cylindrical casing.

25 2. A device of the character described comprising a cylindrical casing, means for closing a portion of the bottom of said casing, means for rotating the casing, a hinged cutter carried by the bottom of the casing and adapted to close the open portion thereof, and means connecting the hinged cutter with the casing rotating means to operate said cutter.

30 3. A device of the character described

comprising a cylindrical casing, means for closing a portion of the bottom of said cylindrical casing, a hinged cutting member secured to the bottom of the casing adjacent the open portion thereof, means for rotating the casing and adapted for vertical movement within the casing, and means connecting said hinged cutter and the casing rotating means for moving the hinged cutter to close the open portion of the bottom of the casing upon vertical movement of the casing operating means.

4. A device of the character described comprising a cylindrical casing, means for closing a portion of the bottom of said casing, a cutting element hinged to the bottom of said casing near the open portion thereof, means for rotating the casing and adapted for vertical movement within the same, and a link connecting the casing rotating means and said pivoted cutter to move the cutter about its pivot to close the open portion of the bottom upon vertical movement of the casing rotating means.

5. In testimony whereof, I affix my signature, in the presence of two witnesses.

CLAUDE D. STILWELL.
